RAILWAY CAR BODY BOLSTER

Otho C. Duryea, Waterbury, Conn., assignor to
 O. C. Duryea Corporation, New York, N. Y., a
 corporation of Delaware

Application October 29, 1936, Serial No. 108,201

16 Claims. (Cl. 105—228)

This invention relates to improvements in railway car body bolsters and it consists of the matters hereinafter described and more particularly pointed out in the appended claims.

5 One of the objects of the present invention is to provide a bolster for a railway car body, wherein the parts are so formed and coordinated as to have a mutual bracing relation whereby a minimum amount of material is employed and the 10 weight is greatly reduced without sacrificing strength.

Another object of the invention is to provide a bolster of this kind which may be made at a low material and labor cost.

15 A further object of the invention is to provide a bolster of this kind especially adapted for use in connection with the well known Duryea cushioned type of underframe, wherein the center sill thereof passes through and has a limited longitudinal cushioned movement with respect to the 20 bolster.

Again, it is an object of the invention to provide a railway car body bolster of a composite type to include preformed metal sheets and a 25 casting so relatively formed as to make it practical to secure the parts together by welding, thus avoiding the cost and other objectionable features in the use of rivets.

The above mentioned objects of the invention, 30 as well as others, together with the several advantages thereof, will more fully appear as I proceed with my specification.

In the drawings:—

Fig. 1 is a top plan view of a railway car body 35 bolster, embodying the preferred form of the invention, with certain parts shown in horizontal section.

Fig. 2 is a bottom plan view of the bolster.

Fig. 3 is a side elevational view of the bolster 40 as the same appears from the torque arm side thereof.

Fig. 4 is a longitudinal vertical sectional view through the bolster as taken on the line 4—4 of Fig. 1.

45 Fig. 5 is a central transverse vertical sectional view through the bolster as taken on the line 5—5 of Fig. 1.

Fig. 6 is a transverse vertical sectional view 50 through the bolster as taken on the line 6—6 of Fig. 1.

Fig. 7 is another transverse vertical sectional view through the bolster as taken on the line 7—7 of Fig. 1.

The improved bolster is of a built up composite 55 type in that the top or cover plate, the bottom or

tie plate thereof and certain other associated parts are made of preformed metallic plates welded together and to a center brace structure preferably made as a one-piece casting. In this manner, the metal forming the bolster may be 5 arranged for the best distribution so that the greatest strength may be obtained with the least weight, and the material and labor cost reduced.

Referring now in detail to that embodiment of the invention illustrated in the accompanying 10 drawings, 10 indicates as a whole the top or cover plate of the bolster and 11 indicates as a whole the bottom or tie plate thereof. The top or cover plate constitutes the tension member of the bolster and the bottom or tie plate constitutes the 15 compression member thereof. Both of these plates are made of suitable gauge sheet metal cut to substantially the same pattern form.

As shown herein, the cover plate 10 is substantially flat throughout its length and has a relatively wide mid portion 12 with parallel side edges, and end portions 13—13 which taper in width toward their extremities. The tie plate 11 is of substantially the same shape as the cover plate. It includes a relatively wide mid portion 20 25 14 with parallel side edges, upwardly and outwardly inclined intermediate portions 15 and end portions 16. These end portions are substantially parallel with the end portions of the cover plate and are spaced closer thereto than the spacing 30 between the mid portions of the cover and tie plates. In the mid portion of the tie plate is a center opening 17, the purpose of which will soon appear.

The end portions 13 and 16 of both plates are 35 operatively connected together by a side sill reinforcement 18 in the form of a channel, with its web arranged vertically and with its flanges arranged horizontally and facing inwardly. In use the horizontal flange of the sill 19 rests directly upon the like top flange of the associated 40 side sill reinforcement channel 18. To bring the top surface of the horizontal flange of the sill 19 flush with the top surface of the major area of the cover plate, the ends of the cover plate are 45 inclined slightly downwardly. This provides a smooth even surface for the floor of the associated car body and which floor is indicated at 20 in dotted lines in Fig. 3.

The sill reinforcement channels are preferably 50 riveted to the associated parts and for this purpose, in the ends of the cover and tie plates, on the longitudinal median line thereof, are openings 21—22 to give access to the parts for the riveting operation.

Disposed between the mid portions 12 and 14 of the cover plate and tie plate respectively, is a bolster center brace structure indicated as a whole as at 23. As here shown, this structure is made as a hollow integral casting. Said casting includes a horizontal top wall 24 and a horizontal partition wall 25 connected together by upright side walls 26 and intermediate upright stiffening ribs 27, some of which are parallel with the side walls 26 and others of which are disposed at a right angle thereto, the ribs joining one another at the intersection. The top wall and the partition wall join at their ends, with depending vertical walls 28, each of which includes laterally spaced flanges 29. Depending from the mid portion of the partition wall is a hollow housing defined by upright end walls 30 and upright side walls 31 of an open formation. The hollow housing mentioned is provided at the bottom with a hollow circular extension 32 that forms the center plate of the bolster as will later appear. This center plate extension is of a diameter to permit it to pass through the opening 17 in the tie plate 11. Centrally of the extension is an upstanding boss 33 for the king pin whereby the finished body bolster is operatively and pivotally connected to its associated truck bolster, not shown. The boss 33 is connected to the walls 30 and 31 of the housing by means of ribs 34. By means of the open formation of the walls 31, access may be had into the bolster to make the proper king pin connection.

At one side of this casting, the walls 28-30 are formed as upright extensions 35 and these extensions are connected together by vertically spaced cross bars 36 by which the cushion gear (not shown) of the Duryea underframe may be operatively connected to the bolster.

The walls 28-29 and 25, before mentioned, define a pair of laterally spaced passageways 37 through the casting and which passageways are open at the bottom. These passageways accommodate the passage of certain channels 38 through the bolster (see Fig. 3) and which channels constitute the center sill of the associate underframe of the Duryea type. The walls 28-30 of the casting 23 are formed with top and bottom guide lugs 39 and 40 respectively for engagement by the said center sill channels. Those portions of the partition wall 25, forming the tops of the said passageways, are further provided with bosses 41 which form limiting abutments or stops for engagement by parts of the center sill (not shown).

Arranged between the end portions of the cover and tie plates outwardly from the walls 28, before mentioned, are pairs of laterally spaced upright, shear resisting diaphragms 42-42 which terminate at their outer ends at the sill reinforcement 18. These diaphragms are spaced apart a distance approximating the spacing between the flanges 29 of the wall 28 and with which flanges the inner ends of the diaphragms engage.

On the bottom surface of each intermediate portion of the tie plate, a transverse plate 43 is secured for operative engagement by a side bearing, not shown. Each plate is preferably secured to the tie plate by the rivets 44. To stiffen the bolster at these points to resist side bearing loads, I provide upright transverse stiffener plates 45 which are welded to the tie plate adjacent the longitudinal planes of the longer edges of each plate 43. Each stiffener plate 45 terminates at its top edge at a point below the cover plate and extends through parts of the diaphragms 42-42

which are cut out as at 46 for the passage of the stiffener plates therethrough. The stiffener plates 45 are preferably welded to the outer surfaces of the diaphragms, adjacent the cut outs 46.

Extending outwardly from that side of the bolster opposite the extensions 35 before mentioned, are laterally spaced torque arms 48-48. Each arm constitutes a straight top arm member 48 and a suitably shaped bottom arm member 50. Both arm members are preferably made of angle bars. In the case of each top arm member, the horizontal flange thereof faces outwardly and the vertical flange faces downwardly. In the case of each bottom arm member, the horizontal flange faces outwardly and the vertical flange faces upwardly.

The inner end of the horizontal flange of each top arm member engages the underside of the top or cover plate 10 and is welded thereto, the vertical flange of the top arm being spaced outwardly from the plane of the wall 28. The inner end of the horizontal flange of each bottom arm engages the top side of the tie plate and is welded thereto and the inner end of the vertical flange of said bottom arm member is spaced outwardly from the plane of the wall 28. The outer end of the vertical flange of each bottom arm abuts and is welded to the outer end of the vertical flange of the associated top arm and a stiffener plate 51 is welded to said flanges midway between the ends of the arm members.

On the bottom surface of the tie plate, in the plane of the sill passageways 37, are provided stiffener ribs 52 which extend longitudinally of the tie plate. Said stiffener ribs are herein shown as plates welded to the tie plate so as to terminate at their inner ends at the opening 17 and terminate at their outer ends at the ends of the mid portion of the tie plate. Instead of making said ribs as separate plates and welding them to the tie plate, they may be formed by pressing portions of the tie plate downwardly by means of suitable coacting dies.

It is apparent that with the various parts formed as described, they may be assembled in several different ways. One practical way to assemble the parts is to turn the top or cover plate upside down and then invert a center brace casting 23 and arrange its top wall 24 in proper relation upon the mid portion of the cover plate. When this casting is properly positioned, lines of welding 55 are run along the corner formed by the junction of the casting wall 28 with the cover plate. Also lines of welding 56 are run along the corner defined by the ends of the walls 26 of the casting with the cover plate.

One diaphragm 42 of each pair thereof is then positioned on the associated cover plate with its inner end engaged against the outer face of the associated flange 29 of a wall 28 and thereafter secured thereto by a line of welding 57. The edge of each of these diaphragms is welded to the cover plate as at 57x in Fig. 7.

A tie plate 11, with the side bearing engagement plate 43, the stiffening plates 45, the torque arm members 50 and with the other stiffener ribs 52 welded thereto, is then applied to the cover plate and casting, with the center plate extension 32 of the casting extending up through the opening 17 in the tie plate. In positioning the tie plate as described, the stiffener plates 45 thereof enter the notches or openings 46 provided therefor in the two shear resisting diaphragms previously welded to the cover plate. This assists in accurately positioning the tie and 75

cover plates, after which a line of welding 58 is run about the corner formed by the base of the extension 32 and that part of the tie plate defining the opening 17 to secure the parts together at this place. When the tie plate has thus been applied, the inner ends of the stiffener plates 52 which abut the center plate extension 32 are welded thereto as at 59.

The side sill reinforcement members 18 are then applied and riveted to the ends of the cover and tie plates. While the thus far completed bolster is in this position, the top arm members 49 of the torque arms 48 may be welded in place and at this time the welding operations may be carried on in a downwardly direction. When said arms are in this position, their outer ends are welded together and a stiffener plate 51 is applied between the two members of each arm.

Thereafter the thus far completed bolster is turned over, right side up and the bottom edges of the two diaphragms now in place may be welded to the tie plate. With only one diaphragm arranged on each side of casting 23, this gives access into the thus far finished bolster to run in a line of welding 51a to connect the bottom edge of the wall 28 to the tie plate. Thereafter the other diaphragms 42-42 may be applied in place and a line of welding 69 applied to those corners defined by the engagement of the now bottom edges of said other diaphragms 42 with the now top surface of the tie plate. Thereafter the top edges of said two last mentioned diaphragms may be welded to the cover plate. All of the welding for the diaphragms 42 is thus formed on the outside thereof.

It is to be noted from the above, that a built up composite bolster is provided which is light in weight, with the parts cooperating with each other to produce the requisite strength, all with a minimum of welding. It is to be noted that these ribs 52 on the tie plate 11 extend across that area thereof defined by the open bottom ends of the sill passageways 37 in the center brace casting so that the tie plate is indeed stiff and rigid at these points. By making the center plate extension 32 as an integral part of the center brace casting and welding the same to the tie plate as before mentioned, certain advantages are inherent. For instance, a better bond is provided between the center plate casting and tie plate, without the necessity of providing registering rivet holes in these parts and without the necessity of difficult rivet work. Also, greater strength is afforded with fewer parts and assembling operations. It is also pointed out that no rivet heads are present on the top surface of the cover plate and therefore, routing out of the flooring of the associated car to accommodate such heads is unnecessary.

It is further to be noted that the greater strength is present in the bolster where it bears the greatest load, viz: at the center thereof and that the ends of the bolster may be made of much lighter weight where the lesser loads are present.

While in describing the invention, I have referred in detail to the form, arrangement and construction of the various parts thereof, as well as to the steps and sequences thereof in assembly, the same is to be considered only in the illustrative sense so that I do not wish to be limited thereto except as may be specifically set forth in the appended claims.

I claim as my invention:

1. In a car body bolster, the combination of a cover plate, a tie plate having a substantially

central opening therein within its edges, a center brace structure disposed between said plates and including a center plate portion extending through said opening so that said center plate portion is entirely surrounded by a portion of the tie plate, and means for securing said cover plate and said tie plate to said center brace structure.

2. In a car body bolster, the combination of a cover plate, a tie plate having a substantially central opening therein within its edges, a center brace structure disposed between said plates and including a center plate portion extending through said opening so that said center plate portion is entirely surrounded by a portion of the tie plate, means for securing said cover plate and said tie plate to the center brace structure, and a weld for securing a part of the center plate portion to that part of the tie plate defining said opening.

3. In a car body bolster, the combination of a cover plate, a tie plate having a substantially central opening therein within its edges, a center brace casting disposed between said plates and including a center plate portion extending through said opening so that said center plate portion is entirely surrounded by a portion of the tie plate, and means for securing said casting to said cover plate and tie plate respectively.

4. In a car body bolster, the combination of a cover plate, a tie plate having a substantially central opening therein within its edges, a center brace casting disposed between said plates and including a center plate portion extending through said opening so that said center plate portion is entirely surrounded by a portion of the tie plate, means for securing the top portion of the casting to the cover plate, and a weld for securing a part of the center plate portion to that part of the tie plate defining said opening.

5. In a car body bolster, the combination of a cover plate, a tie plate having a substantially central opening therein within its edges, a center brace structure disposed between said plates and including a center plate portion extending through said opening so that said center plate portion is entirely surrounded by a portion of the tie plate, means for securing said cover plate and the tie plate to said center brace structure, and means on the underside of said tie plate for stiffening the latter adjacent said opening.

6. In a car body bolster, the combination of a cover plate, a tie plate having a substantially central opening therein within its edges, a center brace structure disposed between said plates and including a center plate portion extending through said opening so that said center plate portion is entirely surrounded by a portion of the tie plate, means for securing said cover plate and the tie plate to said center brace structure, and stiffening ribs secured to the underside of the tie plate adjacent said opening.

7. In a car body bolster, the combination of a cover plate, a tie plate having a substantially central opening therein within its edges, a center brace structure disposed between said plates and having at least one center sill opening extending transversely of said plates and including a center plate portion extending through the opening in the tie plate so as to be entirely surrounded by a portion of the tie plate, and means for securing said cover plate and tie plate to the center brace structure.

8. In a car body bolster, the combination of a cover plate, a tie plate having a substantially central opening therein within its edges, a center brace structure disposed between said plates and

- having at least one center sill opening extending transversely of said plates and including a center plate portion extending through the opening in the tie plate so as to be entirely surrounded by a portion of the tie plate, means for securing said cover plate and tie plate to the center brace structure, and means for stiffening the tie plate in the plane of the center sill opening in the center brace structure.
10. In a car body bolster, the combination of a cover plate, a tie plate having a substantially central opening therein within its edges, a center brace structure disposed between said plates and having laterally spaced, center sill openings each bottomed by a part of the tie plate, said center brace structure including a center plate portion arranged between said center sill openings and extending through the opening in the tie plate so as to be entirely surrounded by a portion of the tie plate, means for securing said cover plate and the tie plate to the center brace structure, and means for stiffening those parts of the tie plate that bottom said center sill openings.
15. In a car body bolster, the combination of a cover plate, a tie plate having a substantially central opening therein, a center brace structure disposed between said plates and having laterally spaced, center sill openings each bottomed by a part of the tie plate, said center brace structure including a center plate portion arranged between said center sill openings and extending through the opening in the tie plate, means for securing said cover plate and tie plate to the center brace structure, and stiffening ribs extending outwardly from the center plate and secured to those parts of the tie plate that bottom said center sill openings.
20. In a car body bolster comprising a cover plate, a tie plate having a substantially central opening therein within its edges, a center brace structure disposed between said plates and including a center plate portion extending through said opening so that said center plate portion is entirely surrounded by a portion of the tie plate, means for securing the cover plate and the tie plate to the center plate structure, and means providing shear resisting diaphragms between those parts of the cover plate and the tie plate outwardly from each side of the center brace structure.
25. In a car body bolster comprising a cover plate, a tie plate having a substantially central opening therein within its edges, a center brace structure disposed between said plates and including a center plate portion extending through said opening so that said center plate portion is entirely surrounded by a portion of the tie plate, means for securing the cover plate and the tie plate to the center plate structure, and means providing shear resisting diaphragms between those parts of the cover plate and the tie plate outwardly from each side of the center brace structure.
30. In a car body bolster, the combination of a cover plate, a tie plate having a substantially central opening therein, a center brace casting disposed between said plates and including laterally spaced center sill openings each defined by inner and outer walls and a top wall, the center sill openings being bottomed by parts of the tie plate, means in said casting providing a hollow box-like bracing structure above said center sill openings, said casting including a center plate portion at the bottom which extends down through the opening in the tie plate, and means for securing the cover plate and the tie plate to the center brace casting.
35. In a car body bolster, the combination of a cover plate, a tie plate having a substantially central opening therein, a center brace casting disposed between said plates and including laterally spaced center sill openings each defined by inner and outer walls and a top wall, the center sill openings being bottomed by parts of the tie plate, means in said casting providing a hollow box-like bracing structure above said center sill openings, said casting including a center plate portion at the bottom which extends down through the opening in the tie plate, and means for securing the cover plate and the tie plate to the center brace casting, and means providing stiffening ribs for these parts of the tie plate which bottom the center sill openings in said casting.
40. As an article of manufacture, a railway car underframe member including a bottom tie member adapted for application to the body bolster of a car having a center plate, said member having an opening adapted to encircle the center plate and be welded thereto.

OTHO C. DURYEA.
